(57) **CLAIM**

The ornamental design for an inhaler, as shown and described.

DESCRIPTION

FIG. 1 is a top, front, left perspective view of an inhaler showing my new design;

FIG. 2 is a front view thereof;

FIG. 3 is a right side view thereof where the left side view is a mirror image;

FIG. 4 is a top view thereof;

FIG. 5 is a bottom view thereof;

FIG. 6 is a bottom, rear, left perspective view thereof;

FIG. 7 is a top, front, left perspective view of the inhaler in a first alternate configuration;

FIG. 8 is a front view thereof;

FIG. 9 is a right side view thereof where the left side view is a mirror image;

FIG. 10 is a top view thereof;

FIG. 11 is a bottom view thereof;

FIG. 12 is a bottom, rear, left perspective view thereof;

FIG. 13 is a top, front, right perspective view of the inhaler thereof of FIGS. 1-7;

FIG. 14 is a top, front, right perspective view of the inhaler thereof of FIGS. 7-12;

FIG. 15 is a top, front, right perspective view of the inhaler thereof in a second alternate configuration;

FIG. 16 is a bottom, front, right perspective view thereof;

FIG. 17 is another top, front, right perspective view thereof;

FIG. 18 is a top view of the inhaler in a third alternate configuration;

FIG. 19 is a bottom view of a first component of the inhaler thereof;

FIG. 20 is a top view of a second component of the inhaler thereof;

FIG. 21 is a top, front, right perspective and exploded view of the inhaler of FIGS. 7-12;

FIG. 22 is a bottom, right, perspective view of the first component in FIG. 19; and,

FIG. 23 is a top right perspective view of the second component of FIG. 20.
